UNITED STATES PATENT OFFICE.

SALIM ELIAS, OF NEW YORK, N. Y.

DESIGN FOR A NEEDLE-BOOK.

SPECIFICATION forming part of Design No. 30,385, dated March 28, 1899.

Application filed February 11, 1899. Serial No. 705,348. Term of patent 7 years.

To all whom it may concern:

Be it known that I, SALIM ELIAS, a citizen of the United States, residing at New York, in the borough of Manhattan and State of New York, have invented and produced a new and original Design for Needle-Books, of which the following is a specification, reference being had to the accompanying drawing, forming part thereof, and in which the book is shown in open position.

As shown in the drawing, the essential feature of my design consists of a rectangular central panel, two rectangular side panels, and two rectangular panels arranged at the opposite-disposed ends of the side panels and having double-lobed outer edges.

A indicates the central panel, and B B' the

side panels. The side panel B has at one end a panel D, having two lobes or scallops *d d*, while the other side panel B' has at its end opposite the panel D a panel D', having two lobes or scallops *d' d'* and corresponding with panel D.

What I claim is—

The design for a needle-book, as herein shown and described.

In testimony that I claim the foregoing as my invention I have signed my name in presence of two subscribing witnesses.

SALIM ELIAS.

Witnesses:

ANGELA ELIAS,
H. C. THULLAY.
